UNITED STATES PATENT OFFICE.

SOPHIE MOSKOVITZ AND PHILIP MOSKOVITZ, OF PHILADELPHIA, PENNSYLVANIA.

HAIR WAVER.

Application filed April 21, 1928. Serial No. 271,674.

Our invention relates to a new and useful improvement in hair curlers and more particularly to the type of hair curler which is adapted to produce the curled or waved effect in the hair, by retaining the hair properly crimped and clamped for a relatively great length of time and without the application of any heat.

Our invention relates more particularly to a hair curler of the character stated, of a very inexpensive and yet of highly efficient and durable construction, comprising one of a plurality of bowed channel members of generally curved cross section, adapted to extend entirely across one side of the head of the wearer, and a relatively thin, flat and normally straight resilient band, hingedly secured to one end of said bowed channel member and having means at the other end thereof for detachable engagement with the juxtaposed end of said channel member, whereby said thin resilient band may be pressed into said channel in a bowed condition and retained therein in clasped position.

The hair curler of our novel construction is adapted particularly for use in making so-called water waves by dampening the hair and then retaining the same crimped within one of a plurality of parallel bowed channel members, by means of a thin resilient retainer band until the hair has dried and set.

For the purpose of illustrating our invention, we have shown in the accompanying drawings forms thereof which are at present preferred by us, since they will give in practice satisfactory and reliable results, although it is to be understood that the various instrumentalities of which our invention consists can be variously arranged and organized and that our invention is not limited to the precise arrangement and organization of these instrumentalities as herein shown and described.

In the accompanying drawings in which like reference characters indicate like parts,

Figure 1 represents a perspective view of the hair waver of our novel construction in actual use.

Figure 2 represents a perspective view of the hair waver of our novel construction shown detached in the closed position.

Figure 3 represents a similar perspective view of the hair waver of our novel construction detached and in a partly opened position.

Figure 4 represents a perspective view, on

an enlarged scale, of the hinged end of the hair waver of our novel construction, illustrating the hinged construction.

Figure 5 represents a perspective view, also on an enlarged scale, of the clasp end of the hair waver, illustrating the detailed construction of the clasp thereof.

The hair waver of our present novel construction comprises a bowed channel member 1 having a longitudinal curvature corresponding generally to the curvature of the side of the head and being curved transversely to a suitable depth so as to produce the desired wave.

One end of the channel member 1 is provided with an aperture 2, in which one end of a resilient retainer band 3 is hingedly secured by an eyelet 4, as shown particularly in Figure 4.

The resilient retainer band 3 is normally straight and is relatively thin and flexible. The opposed end of the retainer band 3 carries a clasp member 5 of a generally scroll formation, deflected substantially at a right angle to the body of the band 3, as shown particularly in Figures 4 and 5.

The clasp member 5 is adapted to engage the free edge 6 of the channel member 1, thereby to detachably interengage the clasp end 5 of the normally straight retainer band 3 with the free end of the bowed channel member 1.

In the preferred embodiment of our invention, two or more similar channel members 1 are provided with interconnecting webs 7, whereby the channel members 1 are retained in spaced and generally parallel relation to each other, as shown particularly in Figures 1 to 3 inclusive.

In this preferred embodiment of our invention the hair is laid flat across the entire waver, as shown particularly in Figure 1, and the retainer bands 3 are then deflected and forced into the respective channels in succession, thereby depressing the hair in successive waves into each of said channel members 1.

Due to the provision of the relatively thin flexible retainer bands 3, the hair is exposed to the action of the air, thereby permitting the more rapid drying and setting of the same.

In order further to facilitate the more rapid drying and setting of the hair, we may perforate the bowed channel members 1 in any suitable manner so as to expose the hair to the action of the air on both sides.

- While in the accompanying drawings we have illustrated our novel hair waver as comprising bowed channel members 1, united by relatively narrow spacing webs or members 7, yet instead of providing merely the relatively small spacing members 7 we may unite the successive bowed channels 1 by a continuous web similar to the web 7, but extending the entire length of the bowed members, 5
- 10 which construction possesses certain advantages. Thus, for instance, the provision of the relatively small or narrow spacing web 7 affords a certain degree of flexibility between the successive bowed members 1 so as to permit the entire waver more readily to conform 15 to the shape of the head. A continuous spacing web extending the entire length of the bowed members, on the other hand, would afford a more rigid construction.
- 20 Due to the resilient character of the normally straight flat retainer bands 3, hair of varying quantities can be accommodated in each of the bowed channel members 1, because the retainer band 3 possesses sufficient yielding qualities to accommodate hair of varying 25 quantities and yet maintain the same pressed tightly into the bowed channel member.

We are aware that the invention may be embodied in other specific forms without departing from the spirit or essential attributes 30

thereof, and we therefore desire the present embodiment to be considered in all respects as illustrative and not restrictive, reference being had to the appended claim rather than to the foregoing description to indicate the 35 scope of the invention.

Having thus described our invention what we claim as new and desire to secure by Letters Patent, is:—

In a device of the character stated, a plurality of relatively rigid bowed channel members, each having a hinge aperture at one end thereof, corresponding relatively thin resilient and flexible retainer bands, each having an eyelet at one end thereof hingedly secured to the apertured end of the corresponding bowed member, a resilient clasp carried by the other end of each of said retainer bands in juxtaposition to the opposed ends of said channel member and adapted for detachable 40 connection therewith, whereby said flexible retainer bands will be retained taut within said channel members, and a web intermediate of adjacent bowed members, retaining 45 the latter in spaced relation to each other. 50

In witness whereof we have hereunto set our hands.

SOPHIE MOSKOVITZ.
PHILIP MOSKOVITZ.
